SHOEHORN

Frank A. Gesell, Belleville, N. J.

Application September 29, 1943, Serial No. 504,236

1 Claim. (Cl. 223—118)

This invention relates to shoe horns and more particularly to an improved shoe horn which will more readily fit the contour of a person's heel when used.

At the present time shoe horns are normally standard size and are usually made from metal or plastic which is substantially rigid. One of the purposes of this invention is to provide a shoe horn which is very flexible and which can adapt itself to the contour of the human heel to more readily allow insertion of the foot into the shoe.

Present day shoe horns of necessity, because of the metal or other material of which they are made, have considerable thickness. This is a disadvantage due to the fact that shoes today, and particularly women's shoes fit very snugly about the heel and the use of a heavy or thick shoe horn tends to distort the shoe.

An object of this invention therefore is to provide a shoe horn which will be very thin, about $\frac{15}{1000}$ of an inch thick which will allow insertion of the foot into the shoe without distortion.

Another advantage of my shoe horn is that it is double ended providing one size for the larger heels and a smaller size for smaller heels.

Other objects and advantages of my invention will appear from the accompanying drawing and description.

Figure 1 is a plan view of a shoe horn embodying my invention;

Fig. 2 is a side view thereof;

Fig. 3 is a cross-sectional view;

Fig. 4 is a cross sectional view taken on the line 4—4 of Fig. 5 showing the shoe horn inserted in the shoe;

Fig. 5 is a sectional view in elevation of the shoe horn placed in the shoe;

Fig. 6 is a cross sectional view taken on the line 6—6 of Fig. 5.

My improved shoe horn 10 is preferably made of flexible pliable plastic material having a high

tensile strength. Preferably the material should be between 10 and 20 one thousandths of an inch thick. The shoe horn is double ended having a wider end member 11 and a narrower end member 12, the wider end member being adapted for use by men while the narrower end member for women. The shoe horn is creased along the lines 14 and 24 so that it will naturally assume the arcuate shape of a person's heel as shown in Figure 3. While it will normally assume an arcuate position it is flexible enough to flatten out without damage. Toward the center portion of my shoe horn I provide lateral projections 15 and 16. These projections limit the insertion of the shoe horn into the shoe so that there is no danger of it being carried in under the heel when the heel is slid into the shoe. As shown in Figures 5 and 6 the projections are of a sufficient distance from the end in each case to allow the working member of the shoe horn to be inserted into the shoe but not to be drawn in by the insertion of the foot. The members 11 and 12 are optionally usable in such manner that one member serves as the handle for the other member while inserted in a shoe at the heel for putting the shoe on the foot of the user.

It will be appreciated that the protruding stops 15 and 16, while not essential to my invention, are highly advantageous in the sense that if they are not provided the shoe horn, due to its flexibility, might be carried in under the heel as the foot is inserted into the shoe and might require the removal of the shoe to free the horn.

I claim:

35 An elongated flexible member having end portions formed for use as shoe horns and a median portion of increased lateral extent forming shoulders for limiting insertion of the respective end portions, when used as shoe horns.
